UNITED STATES PATENT OFFICE.

GEORGE J. NICHOLS, OF MINNEAPOLIS, MINNESOTA.

DESIGN FOR COMBINED SPAT AND LEGGING.

Application filed August 26, 1922. Serial No. 3,567. Term of patent 3½ years.

To all whom it may concern:

Be it known that I, GEORGE J. NICHOLS, a citizen of the United States, residing at Minneapolis, in the county of Hennepin and State of Minnesota, have invented a new, original, and ornamental Design for Combined Spat and Legging, of which the following is a specification, reference being had to the accompanying drawing, forming part thereof.

In the drawing:

Fig. 1 is a view in elevation of the outer side of combined spat and legging for the left foot and leg;

Fig. 2 is a similar view looking from the opposite direction or showing the inside of the device; and

I claim:

The ornamental design for a combined spat and legging, as shown.

GEORGE J. NICHOLS.
